UNITED STATES PATENT OFFICE.

WILLIAM C. SANFORD, OF AMSTERDAM, NEW YORK.

SPINNING-MACHINE, &c.

SPECIFICATION forming part of Letters Patent No. 376,831, dated January 24, 1888.

Application filed May 14, 1887. Serial No. 238,247. (Model.)

To all whom it may concern:

Be it known that I, WILLIAM C. SANFORD, a citizen of the United States, residing at Amsterdam, in the county of Montgomery and State of New York, have invented certain new and useful Improvements in Spinning-Machines, &c.; and I do hereby declare the following to be a full, clear, and exact description of the invention, such as will enable others skilled in the art to which it appertains to make and use the same:

My invention relates to automatic means for use in connection with spinning, doubling, twisting, and winding machines, by which threads are caught and rigidly held whenever a breakage of the same occurs between the feed-rollers and the spinning or winding mechanism; and the object of the invention is to prevent waste of material from a continued feed of the thread after breakage takes place.

In the accompanying drawings, Figure 1 represents in vertical section a portion of a spinning-frame with my invention shown in elevation. Fig. 2 is a front view of my invention, the operating-lever, which rests upon the thread, being cross-sectioned. Fig. 3 is a vertical section in the line *xx* of Fig. 1. Fig. 4 is a horizontal section in the line *yy* of Fig. 3.

In the drawings, A represents a portion of a spinning-frame provided with spools *a a'* and feed-rollers *a'' a'''*.

B is a ring-rail provided with ring *b* for spindle *b'*, carrying bobbin *b''*, for receiving the united threads *c c'*.

D is my improved stopping mechanism, which comprises a base-plate, *d*, and thread-nipping and slotted guide-plate *d'*, thread-nipping plate *E*, operating-lever *F*, and balancing-weight *f*, as shown, or their equivalents. The plate *d'*, formed on and with the plate *d*, is provided with a vertical slot, *d''*, and a headed pivot, *d'''*, on which latter the thread-nipping plate *E* is hung. The nipping-plate *E* is provided with an upright jaw, *e'*, and an arm, *e''*, having a radial or nearly radial slot, *e'''*.

Through the slot *e'''* the end *f'* of the operating-lever *F* is passed. The operating-lever *F* is of suitable curved shape, and is provided with a transverse hook, *f''*, which rests at *C* upon the several united threads between the feed-rollers *a'' a'''* and the central guide, *a'*, of

the spinning-frame. The said operating-lever is fastened, by means of a set-screw, *f''*, to the balancing-weight *f*, through which its end *f'* is passed. The balancing-weight *f* is pivoted between two vertical lugs, *a'' a'''*, of the plate *d* by means of a pivot or short journals at a right angle to the pivot of the vibrating nipping-plate *E*, and it almost balances the weight of the lever *F*, while the hook *f''* rests at *C* upon the several united threads; but when the thread is broken and the lever *F* is deprived of its support at *C* the lever drops, as illustrated by dotted lines in Fig. 1, and the weight *f* assumes the position shown by dotted lines, 65 and allows the full weight of the lever *F* to be utilized in vibrating the thread-nipping plate *E* in a direction at a right angle to the travel of the threads. When the front portion of the operating-lever drops, the rear portion, *f'*, 70 swings up, and by the aid of the slotted extension *e'' e'''* of the thread-nipping plate *E* moves the same upon its pivot *d'''* until the jaw *e'* has passed and covered the slot *d''*, in which position the plate *E* and its jaw *e'*, in conjunction 75 with the guiding and nipping plate *d'*, seize or nip and hold the threads, as illustrated in Fig. 4, so as to stop their further passage toward the feed-rollers. It will be understood that the nipping-plates described are dull on 80 their opposing or passing edges, and that the ends of the broken threads are caught and moved laterally between the two plates and held between these dull edges and the adjoining surfaces of the nipping-plates without being cut, the action being such that they are so firmly held that no more thread can be withdrawn from the spools by the feed-rollers until the nip is caused to cease. In their action the nipping-plates resemble a pair of shears or 85 scissors, with one limb stationary and the other vibrating, but both limbs having dull edges and incapable of cutting. The broken thread being reunited and the hook *f''* being placed upon it, the resulting upward motion of the 90 front portion of the lever *F* and the downward motion of the rear portion, *f'*, of the same move the thread-nipping plate *E* back to its normal position, (shown in Fig. 2,) and the threads *c c'* are released and allowed to move 100 toward the feed-rollers. Thus the slightest loss of thread by continued feed after break-

age is avoided, as the breaking of the thread and its checking by my device are simultaneous.

5 My invention avoids loss of labor and delay in the removal of wasted thread.

It will be apparent that the described invention can be attached to frames of either old or new constructions without removal of or change in the construction of the feed-rollers or other 10 parts of the machines, as is frequently required in the adoption of other stopping devices.

I am aware that various constructions of stop-motions for spinning and twisting machines have been devised and patented, but I 15 am not aware that a combination similar to mine has been contrived, the same comprising an automatic vibrating nipping-plate applied in a novel manner with a stationary guiding and nipping plate and a gravitating lever, as 20 hereinbefore described, said combination causing the ends of the broken threads to be moved aside between nipping surfaces and to be firmly nipped and held between said surfaces until the threads are reunited.

25 What I claim as my invention, and desire to secure by Letters Patent, is—

1. The combination of the nipping-plate E, plate d', and weighted lever F, the said plate E being formed with a slotted extension, as e² 30 e³, and with a jaw, e', and pivoted to the plate d', while the plate d' is provided with a slot, as d², and the lever F connected by one of its ends to the plate E, while its other end is pend- 35 ent upon the threads of yarn being twisted, substantially as described.

2. The vibrating nipping-plate E and the gravitating lever F, in combination with a nipping and guide plate, d', the said vibrating plate being pivoted to the plate d' and moving 40 on its pivot in a transverse direction to the threads being fed to the twisting mechanism, and thereby causing the broken ends of the

threads to be moved laterally between itself and the plate d' and nipped firmly, substantially as and for the purpose described. 45

3. The combination of the vibrating nipping-plate E, formed with a jaw, e', and an extension, e³, having a slot, e², the nipping and guiding plate d', and the gravitating lever F, the latter hung on a pivot and swinging trans- 50 versely to the direction in which the plate E moves, substantially as and for the purpose described.

4. The weight f, pivoted to the plate d, the gravitating lever F, looped or bent at its forward end and having its rear end passed through the weight above the pivot thereof, the vibrating nipping-plate E, pivoted at d' and provided with a slotted extension, and connected to the rear end of the lever F by 60 said slotted extension, and the guiding nipping-plate d', substantially as and for the purpose described. 55

5. The vibrating nipping-plate E, formed with a jaw, e', and an extension, e³, having a slot, e², the nipping-plate d', provided with a pivot, d³, on which the plate E is hung and vibrated, and with a slot, d², the lever F, and the pivoted weight f, said lever having its rear end passed through the pivoted weight f and 70 into the slot e² of the plate E in a direction at a right angle to the pivot of the weight f and the movement of the plate E, and having its front end adapted to rest upon the threads being fed to the twisting-machine, the whole 75 combined and operating substantially as described.

In testimony whereof I affix my signature in presence of two witnesses.

WILLIAM C. SANFORD.
